Attorney

UNITED STATES PATENT OFFICE.

BENJAMIN L. BLOOM, OF SCRANTON, PENNSYLVANIA, ASSIGNOR TO COLLINS SUPPLY
AND EQUIPMENT COMPANY, OF SCRANTON, PENNSYLVANIA.

SPINNING-RING HOLDER.

Application filed June 6, 1927. Serial No. 196,831.

The present invention relates to spinning ring holders for spinning machines, and aims to provide a novel and improved holder for a spinning ring.

5 Spinning ring holders which are in prevailing use are composed of flat sheet metal rings or annular plates having upstanding portions forming supports for the rings, said portions being offset outwardly to receive 10 the rings and to form seats or shoulders on which the rings seat. The traveller is constantly moving, during the operation of the machine, around the ring, and the ends of the traveller frequently contact with the 15 supporting portions of the ring holder in prevailing use, resulting in the supporting portions being cut off. The contact of the traveller with the supporting portions also creates additional tension upon the silk 20 thread, causing excessive stretching and occasional breaking of the thread.

The present invention has for an object to provide a ring holder having novel supporting portions to receive and support the 25 ring in a manner which will avoid the objections incident to the use of the ordinary or well known ring holders, and which will also permit of greater freedom of movement of the traveller, as well as providing 30 other advantages.

The invention is illustrated in the accompanying drawing, wherein—

Figure 1 is a plan view of a spinning ring, partly broken away, assembled with the improved holder.

Fig. 2 is a section on the line 2—2 of Fig. 1.

The spinning ring 7 is of usual construction, and the wire traveller 8 has downwardly offset feet or terminals 9 which move 40 under the ring 7.

The holder 10 comprises a flat annular plate or ring of sheet metal having an upstanding annular flange 11 at its inner edge 45 to assist in guiding the traveller 8. The holder 10 is provided at its outer edge with three upstanding portions 12 between which the ring 7 is disposed with its outer edge

abutting said portions 12. The portions 12 are not offset as usual, and in order to support the ring 7, lugs 13 are struck inwardly from the portions 12, and are inclined inwardly, extending upwardly and inwardly so that their upper edges form seats for the ring 7. The lugs 13 are bent inwardly only 55 slightly from the portions 12, so as not to occupy as much space as the usual offsets, and said lugs 13 form substantial supports for the ring 7 and will not be cut off by the contact therewith of the feet or ends of the 60 traveller 8. In using offsets, according to the prevailing practice, the offsets require more space under the ring 7 than is required by the lugs 13, on account of the bending of the supporting portions, which is not required with the present construction, and with the use of the lugs 13 a neater construction is provided and the ring is also accommodated and supported with a more 65 snug fit. The feet or terminals 9 of the 70 traveller which move under the ring 7 may also be made slightly longer than usual, thereby avoiding the jumping of the traveler out of its path owing to sudden additional tension on the thread from a variety of 75 causes, such jumping of the traveller being experienced with the construction of traveler and holder as used heretofore. The lugs 13 may also be bent inwardly or outwardly to increase or decrease the projection there- 80 of inwardly beyond the portions 12.

Having thus described the invention, what is claimed as new is:

1. A spinning ring holder having upstanding portions to receive a spinning ring 85 between them, said portions having inwardly struck lugs to support the ring.

2. A sheet metal spinning ring holder having upstanding portions to receive a spinning ring between them, said portions 90 having upwardly projecting instruck lugs for supporting said ring.

In testimony whereof I hereunto affix my signature.

BENJAMIN L. BLOOM.
